UNITED STATES PATENT OFFICE

HARLAN E. HUNTSBERY, OF CLEVELAND, OHIO.

CLAM-SHELL BUCKET.

No. 888,088.

Specification of Letters Patent.

Patented May 19, 1908.

Application filed January 18, 1908. Serial No. 411,423.

To all whom it may concern:

Be it known that I, HARLAN E. HUNTSBERY, a citizen of the United States of America, residing at Cleveland, in the county of 5 Cuyahoga and State of Ohio, have invented certain new and useful Improvements in Clam-Shell Buckets; and I hereby declare the following to be a full, clear, and exact description of the invention, such as will enable 10 others skilled in the art to which it pertains to make and use the same.

This invention relates to new and useful improvements in clam-shell buckets and operating mechanism therefor especially adapted 15 for handling iron-ore and similar material.

The object of my invention is to provide a bucket of the type known as a power opening grab, which will be simple and strong in construction, compact in size and capable of 20 stretching over a large area when open.

My invention, therefore, consists in providing new and improved means for suspending the respective halves of the bucket whereby the excavating power of the bucket can 25 be most advantageously applied, all packing of the material avoided and the complete excavation of the material secured.

My invention further consists in the features of construction and combination of 30 parts as described in the specification, pointed out in the claims and illustrated in the accompanying drawings.

In general my bucket comprises two scoops 35 or trays adapted to form a single receptacle or bucket when their front edges are brought into contact. These scoops are suspended from shafts by a combination of arms or links and the power for opening and closing the same is applied through a series of sheaves and 40 ropes. The supporting and operating mechanism is so arranged that no part thereof overhangs or projects beyond the sides or ends of the bucket and consequently will not come in contact with any portion of the 45 vessel or boat where the bucket is being used.

The general arrangement of the parts is such as to secure the minimum height of structure when the bucket is closed and the maximum stretch for the length of arms, thus allowing 50 the bucket to be readily operated in the hold of a vessel between decks or in other comparatively shallow or low places, and the large area covered by the bucket when open permits the same to be used for scraping the 55 ore together thereby supplementing and assisting the scraping devices or hand-work in

getting the ore below the hatchways. Also the great stretch of this bucket, in connection with it being a power closing bucket, enables the operator by "heeling" one scoop to operate the bucket the full stretch in either direction therefrom, thereby making the working area of the bucket equal to twice the actual spread thereof. Therefore if three buckets are being operated, and one of the 60 buckets becomes disabled, the other two buckets can be so manipulated as to practically do all the work of the disabled bucket. Furthermore the scoops are so mounted and supported that, when the bucket is open, the 65 digging edge of each scoop will be further out than the top or rear edge thereof and therefore in operation the digging edge will come in contact with the bulk head or wing of the boat while the top edge of the scoop will be a 70 distance back from either the bulk-head, wing or stanchion which permits all vertical surfaces as well as the horizontal surfaces to be scraped by the edges of the bucket. When the bucket is open the cutting edges and 75 the front side edges of the scoops or trays are in the same plane and therefore when the bucket is lowered into the hold of a boat the entire lower edges of the scoops come in contact with the tank tops and the side edges of 80 the scoops therefore prevent the cutting edges from digging into or in any way injuring the tank tops which would also injure the cutting edges of the scoops. Also when the bucket is open the frame and supporting 85 arms form a strong arch which adequately resists the thrust or strains consequent upon bringing the bucket into contact with the material which is to be excavated.

In the accompanying drawings Figure 1 is 95 a side elevation of the bucket closed. Fig. 2 is an end elevation of same. Fig. 3 is a side elevation showing the bucket open. Fig. 4 is a top plan of the bucket open.

Again referring to the drawings 1 and 2 100 represent the trays or scoops which together form the bucket proper. From a shaft 3 are suspended two pairs of curved arms 4 and 5 and the lower ends of each pair of arms are pivotally secured to the front end of the 105 scoop. The lower ends of said arms are offset so that they are back from the sides of the scoops thereby leaving room for the mounting of sheaves on the outside of said arms which will not project beyond the sides 110 of said scoops. To the respective pairs of arms 4 and 5 are pivotally secured pairs of

links 7 and 8 by means of shafts 9 and 10 respectively which extend between the arms of the respective pairs of arms 4 and 5. The free ends of said pairs of links 7 and 8 are 5 united by a shaft 11. Pairs of arms 12 and 13 are secured at their lower ends to the rear ends of the scoops 1 and 2 respectively and at their upper ends to the pairs of links 7 and 8 respectively by means of shafts 14 and 15 10 respectively which extend between the links of each pair of links. The arms are preferably secured to the supporting links near the center of said links, but this of course may be varied in some constructions. At each 15 end of the shaft 3 is arranged a swinging pulley or guide-sheave 16 which extends out from one side thereof and a swinging pulley or guide-sheave 17 which extends out from the other side thereof. On each end of the 20 shaft 9 is mounted a sheave 18. Near the lower end of each arm of the pair of arms 4 is mounted a sheave 19 and near the lower end of each arm of the pair of arms 5 is mounted a sheave 20. Two opening ropes 23 are 25 provided which extend down at opposite sides of the structure, each of the ropes passing through a pulley 17 then around a sheave 18 and then up where the end is secured to the shaft 3, and two closing ropes are likewise 30 provided, each of which passes through a pulley 16 then around a sheave 19 then around a sheave 20 and back the sheave 19 to which it is secured.

The operation of the bucket will be readily 35 understood. A pull on the closing rope will of course draw the lower ends of the arms 4 and 5 toward each other causing the front ends of the scoops to swing together. As the ends of the scoops approach each other 40 the free ends of the links 7 and 8 swing down thereby lowering the rear ends of the scoops and bringing the same into the proper position to easily pass through the material which is being excavated. When it is de- 45 sired to open the bucket the closing line is slackened and an upward pull on the opening rope causes the free ends of the links 7 and 8 to swing up towards the upper ends of the pairs of arms 4 and 5, and at the same time 50 the upper ends of said arms are drawn down toward said links so that a very powerful and quick movement is secured which will open the bucket against considerable opposition, and therefore when working in clinging or ad- 55 hesive material there is no liability of the bucket becoming stuck in its closed position and the bucket will operate with consider- able facility even when there is a great weight of material actually adhering to the scoops. 60 This feature is also of importance as hereto- fore referred to when it is desired to "heel" one of the scoops and use the other scoop for scraping together the material which is after- wards to be scooped up. The operation of 65 heeling the scoop consists simply, as is prob-

ably understood, in permitting the front end of one scoop to become embedded in a small quantity of the material and, using such a point as a center, operate the other scoop to scrape the material up to and around the 70 quantity which has been left as the heel. In this way an area having a diameter equal to twice the stretch of the scoops can be thor-oughly scraped.

In order to take up and prevent undue 75 strain when the bucket is opened a stop 20 is arranged on each of the links 7 and is de- signed to abut against the ends of the arms 4 and 5 when the bucket is in its farthest open position.

What I claim is,

1. In a clam shell bucket, the combination of a pair of scoops, swinging arms pivotally secured to the front ends of said scoops, links pivotally secured to said arms, arms pivotally 85 secured at their lower ends to the rear ends of said scoops and at their upper ends to said links, means for causing the free ends of said links to approach the upper ends of said first-mentioned arms and means for causing 90 the lower ends of said arms to approach each other, for the purpose set forth.

2. In a clam shell bucket, the combination of a pair of scoops, swinging arms secured to the front ends of said scoops, links pivotally secured to said arms, arms pivotally secured at their lower ends to the rear ends of said scoops and at their upper ends to said links intermediate of the ends of said links, means 95 for causing the free ends of said links and the upper ends of said first-mentioned arms to approach each other so as to open said bucket and means for causing the lower ends of said first-mentioned arms to approach each other so as to close said bucket.

3. In a clam shell bucket, the combination of a pair of scoops, swinging arms secured to the front ends of said scoops, sheaves mounted on the lower ends of said arms, links pivotally secured to said arms, sheaves carried by said links, arms pivotally secured at their lower ends to the rear ends of said scoops and at their upper ends to said links, ropes operatively arranged on the sheaves on the first-mentioned arms and ropes opera- 110 tively connected with the upper ends of said arms and extending over the sheaves on said links.

4. In a clam shell bucket, the combination of a pair of scoops, swinging arms secured to the front ends of said scoops, sheaves mounted on the lower ends of said arms, links pivotally secured at their ends to said arms, sheaves carried by said links, arms pivotally secured at their lower ends to the rear ends of said scoops and at their upper ends to said links intermediate of the ends thereof, ropes operatively arranged on the sheaves on the first-mentioned arms and ropes operatively connected with the upper 115 ends of said arms.

ends of said arms and extending over the sheaves on said links.

5. In a clam shell bucket, the combination of a pair of scoops, arms pivotally secured to the front ends of said scoops, arms pivotally secured to the rear ends of said scoops, a link connecting each arm on the rear ends of said scoops with a corresponding arm on the front ends of said scoops and means for moving 10 said links so as to change the relative position of said arms.

6. In a clam shell bucket, the combination of a pair of scoops, arms pivotally secured to the front ends of said scoops, arms pivotally secured to the rear ends of said scoops, a link connecting each arm on the rear end of said scoops with a corresponding arm on the front end of said scoops, sheaves mounted on the lower ends of said first- 20 mentioned arms, sheaves carried by said links and ropes operatively arranged on said sheaves.

7. In a clam shell bucket, the combination of a pair of scoops, arms pivotally secured to the front ends of said scoops, links connected at their outer ends with the said arms and having their inner ends lying below the upper ends of said arms, and arms secured to the rear ends of said scoops and having their upper 30 ends connected with said links intermediate of the ends thereof.

8. In a clam shell bucket, the combination of a pair of scoops, a shaft, arms hung from said shaft and pivotally secured to the front ends of said scoops, links pivotally secured at their outer ends to said arms, and having their inner ends lying below the upper ends of said arms, arms secured to the rear ends of said scoops and to said links intermediate of 40 their ends, a shaft connecting the inner ends of said links, means for causing the arm-supporting shaft and the link-connecting shaft to approach each other so as to open said bucket and means for causing the front 45 arms to approach each other so as to close the bucket.

9. In a clam shell bucket, the combination

of a pair of scoops, a shaft, arms pivotally hung from said shaft and connected at their lower ends to the front end of the respective 50 scoops, a link operatively secured to each arm, means operatively connecting said links at their free ends, arms connected at their upper ends to said links near the centers thereof and at their lower ends to the 55 rear ends of said scoops, sheaves carried by said links, sheaves mounted near the lower end of each of said front arms and guide pulleys arranged on said shaft.

10. In a clam shell bucket, the combination of a pair of scoops, a shaft, arms pivotally suspended from said shaft and connected at their lower ends with the front ends of said scoops, links pivotally secured to each of said arms, a shaft operatively connecting 60 the free ends of said links, sheaves mounted on said last-mentioned shaft, arms pivotally secured to each of said links near the center thereof and to the rear ends of said scoops, guide pulleys arranged on the front arm supporting shaft, sheaves arranged on the front arms, opening ropes secured to the front arm supporting shaft and extending down around the sheaves on said links and through the guide pulleys and closing ropes arranged on 75 the sheaves on the lower ends of said front arms and then passing up through the guide pulleys, substantially as described and for the purpose set forth.

11. In a clam shell bucket, the combination of a pair of scoops, swinging arms secured to the front ends of said scoops, swinging arms secured to the rear ends of said scoops, rigid links connecting the front arms to the rear arms, and means for moving 85 said links so as to change the relative position of said arms.

In testimony whereof, I sign the foregoing specification, in the presence of two witnesses.

HARLAN E. HUNTSBERY.
